United States Patent Office.

J. S. DU BOIS, OF ST. LOUIS, MISSOURI.

Letters Patent No. 93,975, dated August 24, 1869.

IMPROVEMENT IN RAILROAD-CAR SPITTOON.

The Schedule referred to in these Letters Patent and making part of the same.

To all whom it may concern:

Be it known that I, J. S. Du Bois, of St. Louis, in the county of St. Louis, and State of Missouri, have invented a new and improved Railroad-Car Spittoon; and I do hereby declare that the following is a full, clear, and exact description thereof, which will enable others skilled in the art to make and use the same, reference being had to the accompanying drawings, forming a part of this specification, in which—

Figure 1 represents a vertical central section of my improved railroad-car spittoon.

Figure 2 is an inverted plan view, partly in section, of the same.

Figure 3 is a detail side view of the same.

Similar letters of reference indicate corresponding parts.

This invention relates to a new spittoon to be fitted through the floor of a railroad-car, so that it will at once let all liquid matter escape, while solid articles, such as cigar-stumps, tobacco, &c., will be retained in it until discharged by turning the bottom of the spittoon.

The invention consists in the general combination with the spittoon of two perforated bottoms and spring fastenings, all so arranged that the operation of the device will be entirely satisfactory and perfect.

A, in the drawing, represents a portion of the floor of a railroad-car.

Through a circular, oval, or other aperture of the floor, is fitted the shell B of the spittoon, which shell is of cylindrical or other suitable form, with an outward-projecting flange, a, at its upper end, said flange supporting the spittoon on the floor.

To the sides of the shell B are fitted two springs, C and D, which, with shoulders b, fit under the floor A, to prevent the spittoon from being taken out. Their upper ends reach through the floor, and are concealed by elevated portions of the flange a. When they are pressed in, the spittoon can be removed.

The bottom E of the spittoon is a perforated plate, hinged at e to the shell B, the hinge being below the spring D, as shown.

Above the bottom E is arranged, in the spittoon, a

false bottom, F, which is made of wire netting, or other finely-perforated material.

The screen F is pivoted by a pin, d, which is fitted through the spittoon at right angles to the pin of the hinge c.

One end of the screen is weighted, so that it will swing down as long as not supported by a pin, e, which projects from the bottom E.

The spring C is pivoted by the pin d, so that it can turn on the same, and has a hook, f, at its lower end, as in fig. 3. This hook catches under a pin, g, projecting from the bottom E, and thereby holds the latter closed.

To the spring C is fastened a smaller spring, h, which, with its free end, fits through an aperture in the end of the pin d.

All liquid matter put into the spittoon will flow out through the perforated screen and bottom, while dirt and solid matter will be arrested by the screen, so as not to clog the apertures of the bottom E.

When the spittoon is to be cleaned, the spring C is swung to one side, so as to release the pin g, when the bottom E will drop open. At the same time the support e is withdrawn from the screen, and the same will partly, by its own weight, partly by the action of the spring h, also be swung open, to discharge all matter placed upon it.

Having thus described my invention,

What I claim as new, and desire to secure by Letters Patent, is—

1. A railroad-car spittoon, consisting of the shell B, perforated bottom E, and screen F, all arranged so that liquid matter can always escape, while solid articles are detained by the screen, substantially as herein shown and described.

2. The springs C, D, and h, and pins d, in combination with the hinged bottom E, pivoted screen F, and flanged shell B, all arranged and operating substantially as herein shown and described.

J. S. DU BOIS.
